Attest

United States Patent Office.

V. M. HEATH, OF MORRISTOWN, VERMONT.

Letters Patent No. 94,598, dated September 7, 1869.

IMPROVEMENT IN CLOTHES-RACK.

The Schedule referred to in these Letters Patent and making part of the same.

To all whom it may concern:

Be it known that I, V. M. HEATH, of Morristown, in the county of Lamoille, and in the State of Vermont, have invented certain new and useful Improvements in Clothes-Racks; and do hereby declare that the following is a full, clear, and exact description thereof, reference being had to the accompanying drawings, and to the letters of reference marked thereon, making a part of this specification.

The nature of my invention consists in the construction of a clothes-rack, which can be easily and readily folded up, when not in use, and in the arrangement of the devices hereafter set forth and explained.

The accompanying drawing represents a perspective view of my rack.

Letter A represents the supports, by means of which the rack is secured to the wall, and which have a vertical slot cut in their tops, so that they can be slipped over a screw or pin, upon which they are to hang.

By means of these slots the rack can be put up and taken down in a moment, or if it is desired, to retain it in one place, the lower ends can also be secured by the means of screws.

Or these supports may also be hung up, by means of the hooks B, which extend outward from their sides.

Extending from one support to the other, and pass-

ing out beyond their sides, is the bar C, the ends of which serve as a pivot to the two arms D and G.

The ends of these arms are joined together by the bars H, upon which the clothes are to be hung.

The bar which joins the two arms G together, extends out through its sides, so as to form pivots, on which the arms K turn, and thus these arms and bars may be multiplied indefinitely, there being small braces, a, secured to the sides of the arms, so as to prevent them from dropping too far down.

When there is a small number of pieces only to be dried, only a portion of the rack need be lowered, while the other part remains turned up, out of the way.

Having thus described my invention,

What I claim, and desire to secure by Letters Patent, is—

The combination of the slotted supports A, bars C and H, arms D, G, and K, and braces a, when arranged to operate as herein described, and for the purposes specified.

In testimony that I claim the foregoing, I have hereunto set my hand and seal, this 28th day of June, 1869.
